(57) **CLAIM**

The ornamental design for layers of soap in a transparent container with a sponge, as shown and described.

DESCRIPTION

FIG. 1 is a perspective view of my design for layers of soap in a transparent container with a lid;

FIG. 2 is a top plan view thereof;

FIG. 3 is a bottom plan view thereof;

FIG. 4 is a side elevational view thereof;

FIG. 5 is a top plan view similar to FIG. 1 without the lid and showing a sponge therein;

FIG. 6 is a front end elevational view thereof;

FIG. 7 is a rear elevational view thereof;

FIG. 8 is a left side elevational view thereof;

FIG. 9 is a right side elevational view thereof; and,

FIG. 10 is a sectional view taken along the line 10—10 in FIG. 5 in the direction of the arrows.
